UNITED STATES PATENT OFFICE.

FRANK W. SWIGART, OF ARROYO GRANDE, CALIFORNIA, ASSIGNOR OF
TWO-THIRDS TO T. A. DRANGA AND A. BRIEGER, OF SAME PLACE.

BUCKLE.

SPECIFICATION forming part of Letters Patent No. 502,787, dated August 8, 1893.

Application filed May 29, 1893. Serial No. 475,881. (No model.)

To all whom it may concern:

Be it known that I, FRANK W. SWIGART, a citizen of the United States, residing at Arroyo Grande, in the county of San Luis Obispo 5 and State of California, have invented a new and useful Buckle, of which the following is a specification.

My invention relates to improvements in buckles, the objects in view being to provide 10 a buckle that may be readily cast of malleable iron, which is strong and durable and which is adapted to be attached to a strap without the necessity of sewing or riveting, or the employment of any tools whatever, whereby 15 should a break occur repair may be made without delay and expense.

Other objects and advantages of the invention will appear in the following description and the novel features thereof will be particularly pointed out in the claim.

Referring to the drawings:—Figure 1 is a perspective view of a buckle, a strap being located therein, said buckle being constructed in accordance with my invention. Fig. 2 is a 25 longitudinal sectional view.

Like numerals of reference indicate like parts in both figures of the drawings.

In practicing my invention I form an oblong buckle frame 1, preferably casting the 30 same of malleable iron, and provide said frame near its ends with openings 2 and 3. By the production of the opening 2 a transverse end bar 4 is formed, and by the production of the opening 3 a rear end bar 5 is 35 formed. The buckle frame in rear of the opening 2 is provided with a perforation 6, and in the same is loosely hung a tongue 7. The rear end bar 5 is provided at its inner side with a pair of curved V-shaped teeth 8 40 which extend beyond the plane of the buckle-frame. At the center of the opening 3 there is formed a cross-bar 9, the same being slightly depressed and provided with a central curved gradually reduced stud 10 upon its outer side.

Upon the upper side of the buckle frame immediately in rear of the opening 2 a keeper 11 is formed, and a similar keeper 12 is formed

upon the under side of the buckle frame in advance of the opening 3.

13 designates the strap, the same having 50 the usual perforations, and in order to effect a connection between the strap and buckle frame, the free end of the former is passed under or back of the bar 5, between it and the central bar 9, over the central bar 9, between 55 the central bar and the opening 3, under the buckle frame, and into the keeper 12. The stud 10 of the bar 9 engages with a convenient perforation in the strap, and the curved pointed teeth 8 bind upon the upper side of 60 the strap, and the same is prevented from rising and disengaging with the stud.

From the foregoing description it will be seen that I have produced a buckle of very simple construction, and one which may be 65 readily cast, the same being adapted for ready connection with any ordinary strap and to be adjusted along the strap, and that I avoid in its application the employment of either rivets or stitches.

Having described my invention, what I claim is—

The herein described improved buckle, the same consisting of the oblong plate having the openings 2 and 3 formed adjacent to its 75 front and rear ends respectively, and formed with the end bars 4 and 5, the latter being provided with the inwardly curved teeth 8, the central cross-bar 9 located in the opening 3, depressed below the same, and provided 80 upon its upper side at its center with the curved tapered stud 10, the buckle tongue 7 hung in the opening 2, and the inner and outer keepers 11 and 12 formed in rear and in advance of their respective openings 2 and 3, 85 substantially as specified.

In testimony that I claim the foregoing as my own I have hereto affixed my signature in the presence of two witnesses.

FRANK W. SWIGART.
